United States Patent Office.

FRED. C. BORST AND PHILANDER WONSEY, OF SPENCERPORT,
NEW YORK.

Letters Patent No. 91,075, dated June 8, 1869.

IMPROVEMENT IN MAIL-BAGS.

The Schedule referred to in these Letters Patent and making part of the same.

To all whom it may concern:

Be it known that we, FRED. C. BORST and PHILANDER WONSEY, both of Spencerport, in the county of Monroe, and State of New York, have invented a certain new and useful Improvement in Mail-Bags; and we do hereby declare that the following is a full and exact description thereof, reference being had to the accompanying drawings, making part of this specification, in which—

Figure 1 represents a perspective view;

Figure 2, a cross-section of the top of the bag; and

Figure 3, a view in perspective of the springs removed from the mouth of the bag.

Like letters of reference indicate corresponding parts in all the figures.

Our invention consists in combining with the mouth of the bag an arrangement of springs, for the purpose of holding said mouth open while the bag is being filled.

In the drawings, A indicates the mail-bag, which may be of the usual form.

In the mouth of this bag are sewed, or otherwise secured, two light flat springs *a a*, so bent as to be of elliptic or oval form, and hinged together at the ends, as shown at *b b*, so as to have a free joint action.

To an overlapping flap, B, of the bag, is also sewed, or otherwise attached, another spring, *c*, of similar form to the others, and hinged or jointed to one of them by means of hinges *d d*.

With these springs is connected an ordinary hook and eye, *f g*, so that when the bag is closed it may be secured by lock and key in the usual way.

The novelty in this invention consists in the combination, with the mouth of the bag, of the jointed springs *a a c*.

The moment the hook and eye are disengaged.

the springs *a a*, by their expansion, throw the mouth of the bag open, and the spring *c* throws the flap open, thus expanding and opening the mouth, and retaining it in that position for filling without further attention.

Much difficulty has been heretofore experienced from the flaccidity and yieldingness of the mouth, which made it necessary, in filling, to take hold of the mouth to open it every time a parcel was inserted.

To accomplish the result above described, it will be noticed that the springs are of peculiar construction, being bent of elliptical form and hinged together, and the flap-spring turning at right angles to the others. The ellipsis gives the proper opening, while the binges connect the parts, and yet allow them to turn and depress in closing.

When closed, the springs *c a*, which overlap, fit closely together, face to face, and form a firm connection, which cannot be easily bent or opened, and a single lock secures the whole, thereby avoiding the ordinary looping-strap that is necessary to secure the flexible-mouthed bag.

What we claim as our invention, and desire to secure by Letters Patent, is—

The arrangement of the elliptic springs *a a c*, hinged together as described, when combined with the mouth of bag A, in the manner and for the purpose specified.

In witness whereof, we have hereunto signed our names, in the presence of two subscribing witnesses.

FRED. C. BORST.
PHILANDER WONSEY.
